UNITED STATES PATENT OFFICE.

DANIEL G. SUNDERLAND, OF PROVIDENCE, RHODE ISLAND, ASSIGNOR OF ONE-HALF TO ARTHUR T. PARKER, OF NORTH ATTLEBORO, MASSACHUSETTS.

LACING.

SPECIFICATION forming part of Letters Patent No. 767,720, dated August 16, 1904.

Application filed March 19, 1903. Serial No. 148,521. (No model.)

To all whom it may concern:

Be it known that I, DANIEL G. SUNDERLAND, a citizen of the United States, and a resident of Providence, in the county of Providence and State of Rhode Island, have invented a new and useful Improvement in Lacings, of which the following is a specification.

My invention relates to an improvement in lacings, and has more particularly for its object to provide certain improvements in lacing-tips in which the use of metallic stiffening is obviated.

My invention consists in providing a lacing having its opposite edges at the end portion thereof folded together and cemented, the cement being applied to the adjacent faces of the folded portion.

A practical embodiment of my invention is represented in the accompanying drawings, in which—

Figure 1 represents the two end portions of a lacing. Fig. 2 is a transverse section in the plane of the line A A of Fig. 1; and Fig. 3 is a view of one end of the lacing in its unfolded position before the tip is formed, showing the cement coating upon one face of the lacing.

The lacing is denoted by 1, and the face of each of its end portions is provided with a coating 2 of cement or other adhesive material.

A permanent tip 3 is formed at each end of the lacing 1 by folding the opposite edges 4

of the end portion together, with the coating of cement 2 on the interior, so that the adjacent faces of the folded portion are permanently cemented to each other. 35

By the above means I am enabled to provide a lacing with tips of sufficient rigidity to permit the lacing to be threaded through the eyelets of the article to which it is to be applied 40 without the use of a metallic stiffening-plate.

The tip formed as hereinabove described is furthermore extremely neat in appearance and may be formed without distorting the body portion of the lace and also may be formed 45 without the use of special machinery, all that is required to complete the tip being to coat one face of the end portion with cement, then fold the edges together and press the adjacent faces into contact with each other. 50

What I claim is—

A lacing having a permanent tip formed at each end thereof by folding the opposite edges at each end of the lacing together, the adjacent faces being provided with cement. 55

In testimony that I claim the foregoing as my invention I have signed my name, in presence of two witnesses, this 14th day of March, 1903.

DANIEL G. SUNDERLAND.
